UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

COMBINED BRASSIÈRE AND DRESS SHIELD.

Application filed November 12, 1925. Serial No. 68,522.

This invention relates to a garment worn by women and the object of the invention is to provide a combination garment for the purpose of supporting the bust as well as affording protection from perspiration at the arm pits. In garments of this character heretofore made, some difficulty was had in providing a satisfactory fit of the garment and especially in providing a desirable and snug fit of the protective shields incorporated in the garment at the arm pits where said shields are located. In some constructions in use at the present time, the shoulder straps which support the garment from the shoulders of the wearer are secured to the arm pit shields rather than to the body of the garment with the result that said shoulder straps are positioned over the shoulders at such a point where they can readily slide off causing the shields to drop away from the arm pits.

The main object therefore, of this invention is to provide a garment of the character herein mentioned and in which the garment will properly fit the wearer and will hold the protective arm pit shields in their proper positions at all times despite movements of the body.

With these objects and such other objects as may hereinafter appear, in view, I have devised the particular arrangement of parts hereinafter set forth, and more particularly pointed out in the claim appended hereto.

Reference is to be had to the accompanying drawing, forming a part hereof, in which

Figure 1 is a front elevation of my improved garment; and

Figure 2 is a plan view of the same.

Throughout the various views of the drawing, similar reference characters designate similar parts.

In the preferred embodiment of my invention as disclosed in the accompanying drawing, 1 indicates the front part of the body of the garment and 2 indicates the rear. The entire body of the garment is preferably made of a continuous strip of light-weight fabric, particularly an open mesh knitted fabric.

50 The body of the garment is made full and is contracted about its upper and lower edges by means of elastic bands 3 and 4 which are secured along the edges of the body. Through this construction, a snug and even fit of the garment is assured as the same is

resiliently contracted about the parts of the body, the front area 1 of the garment being drawn smoothly and evenly over the bust and affording support therefor.

At 5 and 6 are the arm pit shields, each of which comprises a body flap 7 and an arm flap 8, said flaps 7 and 8 being joined on a curved line 9 in the conventional manner.

The body flap 7 is secured within the body of the garment and rests against the body of the wearer. The arm flap 8 is provided with a supporting loop 10 which fits over the arm of the wearer and holds the flap in position.

The upper edge of the body of the garment is shaped in such a manner that it 70 enables suitable shoulder straps 12 to be secured to it and support the garment in such a way that the shields are held in their proper position and cannot readily fall away from the arm pit areas.

It will be seen that the widest part of the body of the garment is located just in front of and directly behind the arm pit shields or in other words, the top edge of the body of the garment extends out as at 14 on a 80 substantially straight line from the highest point of the body flaps 7 on the shields. Thus, the shoulder straps 12 being secured to the upper edge of the body at its widest points and at a distance from the location 85 of the arm pit shields are so positioned that they rest over the shoulders at some little distance from the arm pits and thus rest upon a substantially horizontal part of the shoulder and cannot readily slide therefrom.

These straps 12 being so located maintain their position and tend to hold the arm pit shields securely at their proper positions. Said straps 12 are aided in maintaining their 90 respective positions on the shoulders of the wearer and the positions of the shields are maintained at the arm-pits by reason of the fact that parts 14 of the elastic top edge of the garment lie between the points of secure- 95 ment of the shoulder straps 12 and the arm- pit shields. The straps 12 thus exert an elastic upward pull on the shields and holds them in position.

The upper edge of the garment between the points of location of the straps 12 are 105 downwardly curved as is clearly disclosed in Figure 1.

From the foregoing, it is obvious that my invention is not to be restricted to the exact embodiment shown, but is broad enough to 110

cover all structures coming within the scope of the annexed claim.

What I claim is:—

An article of the class described consisting of a garment having a body portion composed of a continuous strip of light, open-mesh fabric adapted to extend around the body of the wearer and enclose the busts, the upper and lower edges of said strip being made expandable by means consisting of elastic bands secured along said edges, arm pit shields secured in said body, each of said shields being composed of a body flap and an arm flap, the body of the garment

having its widest parts located in front of 15 and at the back of said shields, the top edges of the widest parts of said strip extending at least as high as the top of the body flap on each shield, and shoulder straps secured to the expandible top edges of the strip at 20 positions remote from the shields, so that parts of the expandible top edge of the strip are located between the point of securement of the shoulder straps and the shields.

Signed at the city, county and State of 25 New York, this 6th day of November, 1925.

VICTOR GUINZBURG.
